UNITED STATES PATENT OFFICE.

EMMIT G. LATTA, OF SYRACUSE, NEW YORK

TYPE-WRITING MACHINE.

1,115,077.

Specification of Letters Patent. Patented Oct. 27, 1914.

Application filed February 15, 1911. Serial No. 608,657.

To all whom it may concern:

Be it known that I, EMMIT G. LATTA, a citizen of the United States, residing at Syracuse, in the county of Onondaga and 5 State of New York, have invented a new and useful Improvement in Type-Writing Machines, of which the following is a specification.

This invention relates to improvements 10 in front strike or visible writing typewriting machines in which the type-bars are mounted on a supporting segment which is adapted to be shifted for placing one or another of the sets of type on the type-bars in 15 printing relation to the platen.

One object of the invention is to provide a typewriting machine of the Moyer make with a shiftable type-bar segment and adapt various features of the machine for co-operation 20 with such a shiftable segment, as herein-after described and set forth in the claims.

Other objects of the invention are to provide a typewriting machine having a shiftable type-bar segment with efficient and 25 practical mechanism for operating the carriage escapement, and, preferably, the ribbon vibrating device also, by the direct action of the type-bars; also to arrange and connect the parts of the machine in such a 30 way that they can be assembled and dismounted with ease and rapidity; also to connect the ribbon vibrator lever directly to the universal bar without the use of intermediate or separate loose connections, and 35 to do this in a way that permits of different motions of the vibrator for moving either one of a plurality of different portions or fields of the ribbon to and from position for printing, and permits the vibrator to be 40 thrown out of action; and also to improve visible writing typewriting machines in the other respects hereinabove described and set forth in the claims.

In the accompanying drawings, consisting of five sheets: Figure 1 is a longitudinal sectional elevation of a typewriting machine embodying the invention. Fig. 2 is a fragmentary similar sectional elevation showing the position of the parts when the segment is 50 shifted. Fig. 3 is a longitudinal sectional elevation, on a reduced scale, of the top plate of the machine. Fig. 4 is an enlarged sectional elevation of the operating means for the ribbon vibrator. Fig. 5 is a plan view, 55 partly in section, of the machine, the car-

riage being removed and the carriage guide being partly broken away to disclose the underlying parts. Fig. 6 is a rear elevation thereof partly broken away and partly in section, in line 6—6, Fig. 1. Figs. 7 and 8 are respectively a fragmentary longitudinal sectional elevation and a rear elevation, partly in section, of a modified construction.

Like reference characters refer to like parts in the several figures.

The construction illustrated in Figs. 1-6 will be first described.

A represents the main frame of the machine; B the top plate thereof; C the platen carriage which supports the platen c; D the carriage escapement; E one of the type-bars which are pivoted in an arc below the carriage so that the type-bars can swing upwardly and rearwardly to make the impressions at the front side of the platen; F the key levers and f one of the auxiliary levers operated thereby for actuating the type-bars. These parts, except as hereinabove explained, are constructed, arranged and operated as in the Moyer typewriter and are illustrated to show their relation and coaction with the other parts of the machine.

The top plate B is a single casting of substantially uniform thickness throughout which is removably secured on the main frame A, for instance, by screws b, Fig. 5, at the four corners of the top plate. The front and rear portions of the top plate are in different horizontal planes and the connecting middle part is curved as shown best in Fig. 3. The middle part has two raised side portions b' b', Figs. 3 and 5, forming forwardly inclined flat seats for a carriage track or guide casting B'. The central part of the top plate is removed or provided with an opening b² having large front and rear portions and a narrow connecting portion to permit the type-bars to swing to the platen and to admit the universal bar, ribbon vibrator and other parts when assembling them in the machine. The horizontal front portion of the top plate is preferably provided at opposite sides with depressions b³ having inclined bottoms to enable the ribbon spools, one of which is shown at b⁴, Fig. 1, to be arranged in an inclined position with their front lower edges below the surface of the front part of the top plate so as to deliver the ribbon in line with the ribbon vibrator.

The carriage track casting B' supports

the guide or track on which the carriage travels transversely of the machine. The carriage track or guide b^5 shown is of the ball bearing type used in the Moyer machine, but a track or guide of any other suitable sort could be used. The track casting B' is rigidly secured on the inclined seats b' of the top plate, for instance, by four screws b^6 , two of which are shown in Fig. 5. 10 By the use of a separate track casting secured on the top plate the machine can be readily supplied with track castings of different lengths suitable for different length carriages.

15 The carriage escapement D is mounted on a suitable bearing or portion d on the rear central portion of the track casting B' , the shaft d' of the escapement wheel being, as usual, provided at its front end with a gear 20 pinion d^2 which meshes with a rack bar d^3 on the carriage.

G represents the segment or support for the type-bars. The segment preferably consists of a curved or segmental casting 25 having a slotted flange projecting forwardly from its upper edge in which hangers g for the type-bars are secured by a clamping plate g' and screws g^2 passing through the plate and between the hangers into the segment, as in the Moyer machine. The segment is movably mounted so that it can be shifted vertically on a central arm h and two side arms h' the front ends of which are pivoted in slotted lugs h^2 on the rear side of the segment. The side arms h' are rigidly secured at their rear ends to a rock shaft H which is suitably journaled at its ends on the opposite sides of the main frame, and the central arm h is forked and 40 has the rear ends of its two branches pivoted in lugs h^3 projecting upwardly from a bar h^4 which is rigidly secured to the rear portion of the main frame and to which the rear ends of the key levers are pivoted. The 45 segment-supporting arms are parallel and thus hold the segment upright in its normal and shifted positions.

I represents a cam or cam lever for shifting the segment. This shifting cam is fixed 50 centrally on a horizontal rock shaft i and is provided with a cam slot in which works a roller i' journaled on a bracket i^2 which is secured in any suitable way to and projects forwardly from the middle of the segment. 55 The end portions of the cam slot are preferably substantially concentric with the axis of the cam so that the segment will be locked from movement when the roller enters either of these end portions of the slot. The rock shaft i is journaled at its ends on the sides of the main frame and has rigid forwardly projecting arms i^3 at its opposite ends which rest on the upper rocker-shaped edges of 60 shift key-levers i^4 fulcrumed at i^5 between their ends. One of the shift key-levers is

shown in Fig. 1. By depressing the front end of either of the shift key-levers the rock shaft and cam I are rocked with an accelerating motion and shift the segment, together with the type-bars and other parts supported thereby, from the position shown in Fig. 1 to that shown in Fig. 2. A suitable spring i^6 , Fig. 6, on one end of the rock shaft i acts to start the rock shaft and cam from the shifted position as soon as the shift key-lever is released. When the roller i' passes out of the concentric end portion of the cam slot the weight of the segment and the parts thereon will force the cam back to its normal position. A spring (not shown) is usually employed to partially support the weight of the shifting parts and reduce the exertion necessary to effect the shift. The location of the shift cam centrally under the shifting parts or substantially at the center of gravity thereof makes the shift action quick and easy. 70

The segment is preferably mounted and shifted as above described, but it could be differently mounted and shifted by other means. 85

As indicated by the shade lines in Figs. 1 and 2, both the central key-lever F and the auxiliary lever f are slightly offset sidewise where they pass the shift cam to make room 95 for the movement of the cam between these closely arranged parts.

The universal bar, as heretofore in the Moyer typewriter, consists of a rock shaft which is operated by one or more actuators 100 which are struck and moved by the type-bars as they approach the platen. K represent the universal bar actuators and L the universal bar.

Two actuators K are shown in the construction illustrated in Figs. 1-6 of the drawings. They consist of two curved bars arranged over the pivoted ends of the type-bars so that each actuator is adapted to be struck and actuated by any one of the type-bars on the adjacent half of the segment just before the type-bar reaches the platen. Each actuator is supported by two bars k k' which are rigidly secured to and extend rearwardly from the actuator and are pivoted to the upper ends of arms k^2 k^2 extending upwardly and inwardly from a rock shaft k^3 journaled on the segment, for instance between the two pivot lugs k^4 on the rear side of the segment. The inner supporting bars k' k' of the two actuators extend beyond the arms k^2 k^2 of the rock shafts and are pivotally connected to the upper ends of links k^5 k^5 which are suitably pivoted at their lower ends to the rear ends of 120 brackets k^6 k^6 . These brackets are rigidly secured to and project rearwardly from the segment. The supporting bars k k' are preferably formed from sheet metal stampings and have lateral projections at their 130

front ends which are bent to fit the actuators, to which they are riveted, and the inner bars k' have cross pieces k'' at their rear ends which are slightly twisted so as to stand vertically in front of the lower ends of arms l which are fixed to and depend from the universal bar L . The rock shafts k^3 k^4 cause a corresponding motion of both ends of the actuators when struck by the type-bars regardless of the point at which the actuators are struck, thus insuring a uniform action of the universal bar and the parts operated thereby, and the connection of the links k^3 k^4 to the extensions of the bars k' k' acts to retain the actuators K K' in their proper relation to the type-bars and cause them to move in a substantially horizontal direction. In the normal position of the segment, shown in Fig. 1, the upper parts of the rear ends of the bars k' k' rest against the lower ends of the arms l l of the universal bar, and when the segment is shifted the lower parts of said rear ends rest against the arms l l , as shown in Fig. 2. Therefore the action of the universal bar is the same in both positions of the segment.

k^5 k^6 represent springs for returning the actuators to the normal position after actuation. Coil springs are shown for this purpose connected at their rear ends to the actuator bars k' k' and at their front ends to a bracket k^9 secured to the segment.

The universal bar L is preferably journaled on end pivots l' l' which are fixed by arms l^2 to a supporting rod l^3 which is arranged to slide endwise in bearings l^4 on the underside of the track casting B' . The supporting bar is detachably connected, for instance, by a pin l^5 , Fig. 6, with a shifting lever or device (not shown) whereby the universal bar can be readily adjusted endwise to either of four different positions. The pivots l^4 l' for the universal bar preferably extend through guide holes in the bearings l^4 .

l^6 represents a spring for returning the universal bar to the normal position. The spring shown connects one of the universal bar arms l to a bracket l^7 fixed to the supporting rod l^3 , so that the spring is not affected by the adjustment of the universal bar. The universal bar operates the carriage escapement D preferably by an arm l^8 which projects rearwardly from the universal bar and is connected by a link l^9 to the pawl lever of the carriage escapement.

M represents the ribbon vibrator or guide for vibrating the ink ribbon m to and from the printing position between the type-bars and the printing point of the platen. The vibrator, which may be of the construction shown or of any other suitable construction, is preferably arranged to reciprocate vertically on a stationary upright guide m' and is connected at its lower end to a vibrat-

ing or operating lever m^2 . As shown, the vibrator guide m' is rigidly secured by screws, or otherwise, to the front end of a forwardly projecting extension m^3 of the track casting B' , and the vibrator M is confined between the rear side of the guide m' and a line gage and center scale m^4 which is secured to the rear side of the vibrator guide m' . The lower portion of the vibrator extends downwardly through a slot in the extension m^3 of the track casting B' and has a rearwardly bent lower end which removably engages in a slot in the front end of the vibrator lever m^2 . The vibrator and its guide have registering holes through which the scale on the scale bar m^5 of the carriage can be seen, and the vibrator is provided with an index or pointer m^6 cooperating with said scale to indicate the position of the printing point. The upper ends of the vibrator M , vibrator guide m' and the line gage m^4 are slotted centrally, as shown, to allow the heads of the type-bars to strike the ribbon in making the impressions.

The vibrator lever m^2 is suitably fulcrumed between its ends at m^7 on the underside of the track casting B' and is provided at its rear end with a toothed segment m^8 . Between this segment and its fulcrum the lever is provided with an opening and a second toothed segment m^9 . N represents an arm rigidly secured to the universal bar and provided at its end with teeth which are adapted to mesh with the toothed segment m^8 , and n is an arm located at one side of the arm N and provided with offset teeth at its end adapted to enter the opening in the lever and mesh with the toothed segment m^9 . Preferably the arms N and n are separated by a spacing washer n' , these three parts being riveted together and rigidly secured to the universal bar by soldering or otherwise, and the arm N is made in one piece with the escapement actuating arm l^8 .

In the position of the parts shown in Figs. 1 and 5, the teeth of the arm N mesh with the teeth m^8 at the rear end of the vibrator lever and when the machine is operated the upper portion of the ribbon, or the upper field thereof, in the case of a ribbon having different fields, will be vibrated to and from the printing position. By moving the universal bar to the right, as viewed in Fig. 6, the teeth of the arm N are moved out of mesh with the teeth m^8 of the vibrator lever and the teeth of the other arm n are placed in mesh with the other teeth m^9 of the vibrator lever and then the lower portion or field of the ribbon will be vibrated to and from the printing position when the machine is operated. If the universal bar is moved to the left, to a third position, the vibrator lever is freed from both of the arms N and n and the ribbon vibrator will then remain inactive when the machine is

operated, thus permitting the cutting of stencils.

The lower ends of the arms l of the universal bar are provided with cross pieces or lateral extensions of sufficient width to be engaged by the actuator bars $k' k'$ in either of the three positions of the universal bar just mentioned. If, however, the universal bar is moved still farther to the left, the lower ends of the arms l are moved out of line with the actuator bars $k' k'$, and then either of the actuators K can be moved rearwardly from above the type-bar hangers g so that the hangers can be detached from the segment by loosening their securing screws and disconnecting the type-bars from their actuating links without removing the clamping plate g' for the hangers. The lower end of the actuating link l' for the escapement swings laterally when the universal bar is shifted, but the movement thereof is not great enough to interfere with the perfect action of the escapement in the three operating positions of the universal bar. By locating the escapement operating arm l' of the universal bar over the rear portion of the top plate, as shown in Fig. 1, providing the openings in the top plate, and detachably connecting the universal bar to its shifting device, the track casting R' with the complete carriage, universal bar, escapement and ribbon vibrating mechanism can be detached from the top plate, by simply removing the securing screws for the casting, detaching the ribbon from the vibrator, and disconnecting the draw-band n' that connects the carriage to its spring driving drum. This is a great convenience in assembling, cleaning and repairing the machine, and in changing it for carriages of different lengths. It will be observed that the universal bar is not connected to the actuators on the segment and consequently there are no parts requiring to be disconnected to permit the removal of the top plate or the track casting with the parts supported by the same.

The ribbon feeding and reversing mechanism form no part of this invention and are therefore not shown or described, but this mechanism is mounted as heretofore, on the top plate B , and as the ribbon spools and the vibrating mechanism are also mounted on the top plate, as shown, it will be evident that the top plate with the complete ribbon operating mechanism, together with the other parts mounted on the top plate, can be removed from the machine by simply detaching the top plate and without disconnecting any other parts.

O represents a center guide for properly guiding the type-bars to the printing point on the platen. The center guide is secured by screws, or otherwise, to an upwardly projecting horn or extension o on the middle

portion of the segment. This horn curves rearwardly just above the segment or has a recessed front side otherwise formed to afford room for the actuators K to be moved to the rear far enough to permit the detachment of the type-bar hangers from the segment, as before explained. The center guide O extends upwardly and forwardly from the segment to a point in front of the lower end of the vibrator guide m' , then vertically in front of the latter, and its reduced upper end o' extends rearwardly into the slotted upper end of the vibrator guide. This upper end o' of the center guide is slotted to receive the guiding heels or parts o^2 at the outer ends of the type-bars. The center guide, which shifts with the segment G , has an elongated opening o^3 to enable the scale bar m^3 to be seen through the openings of the ribbon vibrator M and its guide m' in either position of the center guide, and the center guide also has a larger opening o^4 below the opening o^3 that admits the lower end of the vibrator guide, the vibrator, and the front end of the vibrator lever m^4 when the center guide is in the raised or shifted position. While the center guide O shifts with and thus always retains the same relation to the type-bars, the vibrator guide m' is stationary and remains in the same relation to the vibrator M .

P represents a back stop, or rest, for supporting the outer ends of the type-bars in the normal position thereof. This back stop is also supported from the segment so as to shift therewith, for instance, by posts p which are rigidly secured to the ends of the segment in any convenient way and project forwardly therefrom. The back stop or rest, as shown in Fig. 1, preferably consists of a chain composed of center blocks and side links pivotally connected by rivets, and is provided with a top strip or pad p' of leather or other suitable noise-preventing material. The blocks and links meet on radial lines with only enough clearance to permit a very limited movement thereof on the rivets, so that the back-stop or rest retains a segmental form and only a limited flexing thereof is permitted. The end blocks are pivoted on the front ends of the supporting posts p . The springs that restore the type-bars cause the bars to press equally on the back stop except in returning from the platen, when the type-bars strike the back stop with sharp blows which cause the chain to flex slightly and by its inertia to absorb the force of the blows without offering the resistance of a solidly supported back stop to cause the type-bars to rebound. The slight flexing of the chain at the point where it is struck by the returning type-bar tends to straighten the chain at both sides of that point, and this transmits a slight impulse to some of the adjacent type-bars so that their

inertia is added to that of the chain to absorb the shock. The result is that the tendency of the type-bars to rebound is practically overcome.

6 Figs. 7 and 8 show a modified construction of the segment, and universal bar mechanism which is less expensive than that before described. In this construction, G' represents the segment. The type-bars E' are pivoted on the segment by a curved pivot wire G'', thereby dispensing with the separate hangers and bearings used in the first construction. A single curved universal bar actuator K' is used which is long enough to 15 be struck by all of the type-bars. It is supported by two rock-shafts q q' journaled one in rear of the other in brackets q'' projecting rearwardly from the segment G' and having upright arms q³ and q⁴, respectively, which 20 are pivoted to supporting bars q⁵ projecting rearwardly from the actuator K'. The universal bar L' has a single pendant arm q⁶ pivoted to the rear end of a link q⁷ which at its front end has a pin and slot connection q⁸ 25 with a bracket q⁹ on the actuator. The pivot between the link and the actuator normally occupies a position below the level of the pivot between the link and the arm q⁶, and when the segment is shifted the former 30 pivot occupies a position a corresponding distance above that level, so that the action of the escapement and of the ribbon vibrator will be the same in both the normal and shifted positions of the segment. The pin 35 and slot connection q⁸ allows the actuator to return to normal position in advance of the return of the universal bar, and the connections at the ends of the link are loose enough to permit the universal bar to be moved to 40 change the throw of the ribbon vibrator as before described, without affecting the action of the universal bar. This segment is mounted and operated in the same way as that first described and, as in the first construction, the universal bar actuator, the center guide O' for the type-bars, and the back stop P' for the type-bars are supported by and shift with the segment. The segment and the parts supported thereby with but 45 slight changes in one or two of the parts, are interchangeable with the corresponding parts in the construction first described. This modified construction is less desirable than that first described, but it involves a 50 greatly reduced number of parts and is therefore desirable for use in cheaper machines, as it enables the manufacturer to produce machines of two grades with but little more expense than for one.

60 While it is one of the objects of this invention to actuate the operating mechanism for the escapement, and also preferably for the ribbon vibrator, by means supported by a shiftable segment carrying type-bars provided with a plurality of sets of type, the

invention is not necessarily restricted in application to a machine having such a shiftable segment as it is desirable for some purposes to support the escapement actuating means on a segment which does not shift 70 whether provided with type-bars having a single set of type, or more than one set of type and used with a shifting latent.

I claim as my invention:

1. In a typewriting machine, the combination with a main frame, a platen carriage, a carriage escapement, a series of pivoted type-bars, and a supporting segment for the type-bars, of means for actuating the escapement comprising an actuator supported by the segment and actuated by a plurality of the type-bars, substantially as set forth. 75

2. In a typewriting machine, the combination with a main frame, a platen carriage, a carriage escapement, a series of pivoted type-bars, and a supporting segment for the type-bars, of means for actuating the escapement comprising a curved actuator mounted on the segment in position to be 80 actuated by a plurality of the type-bars, substantially as set forth. 85

3. In a typewriting machine, the combination with a main frame, a platen carriage, a carriage escapement, a series of pivoted type-bars, and a supporting segment for the type-bars, of means for actuating the escapement comprising a plurality of curved actuators mounted on the segment and each adapted to be actuated by a plurality of the type- 90 bars, substantially as set forth. 95

4. In a typewriting machine, the combination with a main frame, a platen carriage, a carriage escapement, a series of pivoted type-bars, and a supporting segment for the 105 type-bars, of means for actuating the escapement comprising a curved actuator arranged to be actuated by a plurality of the type-bars, and a pair of swinging supports for the actuator arranged one in rear of the other and both in rear of the actuator, substantially as set forth. 110

5. In a typewriting machine, the combination with a main frame, a platen carriage, a carriage escapement, a series of pivoted type-bars, and a supporting segment for the type-bars, of means for actuating the escapement comprising a curved actuator arranged to be actuated by a plurality of the type-bars, and a pair of swinging supports for the actuator pivoted one in rear of the other on the segment, substantially as set forth. 115

6. In a typewriting machine, the combination with a main frame, a platen carriage, a carriage escapement, a series of pivoted type-bars having a plurality of sets of type, and a shiftable supporting segment for the type-bars, of means for actuating the escapement in the different positions of the seg- 120

- ment comprising an actuator supported by the segment and adapted to be actuated by one or more of the type-bars, substantially as set forth.
- 5 7. In a typewriting machine, the combination with a main frame, a platen carriage, a carriage escapement, a series of pivoted type-bars having a plurality of sets of type, and a shiftable supporting segment for the 70 type-bars, of means for actuating the escapement in the different positions of the segment comprising a plurality of curved actuators supported by the segment each in position to be actuated by a plurality of 75 type-bars, substantially as set forth.
- 10 8. In a typewriting machine, the combination with a main frame, a platen carriage, a carriage escapement, a series of pivoted type-bars having a plurality of sets of type, 80 and a shiftable supporting segment for the type-bars, of means for actuating the escapement in the different positions of the segment comprising a curved actuator arranged to be actuated by a plurality of the type-bars, and 85 supporting means for the actuator comprising a rock-shaft mounted on the segment and having arms pivotally connected to the actuator, substantially as set forth.
- 15 9. In a typewriting machine, the combination with a main frame, a platen carriage, a carriage escapement, a series of pivoted type-bars having a plurality of sets of type, and a shiftable supporting segment for the 90 type-bars, of means for actuating the escapement comprising an actuator arranged to be actuated by one or more of the type-bars, and means supported independently of the 95 segment in relatively fixed position and disconnected from said actuator but actuated thereby for operating the carriage escapement and the ribbon vibrator, substantially as set forth.
- 20 10. In a typewriting machine, the combination with a platen carriage, a series of pivoted type-bars having a plurality of sets of type, a shiftable supporting segment for the type-bars, and a carriage feed escapement and ribbon vibrator supported in relatively fixed positions, of means for actuating 100 the escapement and the ribbon vibrator in the different positions of the segment including an actuator supported by the segment and actuated by one or more of the type-bars, substantially as set forth.
- 25 11. In a typewriting machine, the combination with a platen carriage, a series of pivoted type-bars, a supporting segment for the type-bars, and a carriage escapement, of an actuator supported by the segment and 105 adapted to be actuated by one or more of the type-bars, and means supported independently of the segment and actuated by said actuator for operating the carriage escapement, substantially as set forth.
- 30 12. In a typewriting machine, the combination with a platen carriage, a series of pivoted type-bars, a supporting segment for the type-bars, and a carriage escapement, of an actuator supported by the segment and adapted to be actuated by one or more of the type-bars, and means supported independently of the segment and disconnected from said actuator but actuated thereby for operating the carriage escapement, substantially as set forth.
- 35 13. In a typewriting machine, the combination with a platen carriage, a series of pivoted type-bars having a plurality of sets of type, a shiftable supporting segment for the type-bars, and a carriage escapement, 80 of an actuator supported by the segment and adapted to be actuated by one or more of the type-bars, and means supported independently of the segment and actuated by said actuator in the different positions of the 85 segment for operating the carriage escapement, substantially as set forth.
- 40 14. In a typewriting machine, the combination with a platen carriage, a series of pivoted type-bars, a supporting segment for 90 the type-bars, a carriage escapement, and a ribbon vibrator, of an actuator which shifts with the segment and is adapted to be actuated by one or more of the type-bars, and means supported independently of the 95 segment in relatively fixed position and disconnected from said actuator but actuated thereby for operating the carriage escapement and the ribbon vibrator, substantially as set forth.
- 45 15. In a typewriting machine, the combination with a main frame, a platen carriage, a carriage escapement, a series of pivoted type-bars, and a supporting segment for the type-bars, of means for shifting said 100 segment to place the type-bars in different printing relations to the platen, and means for actuating the escapement comprising an actuator arranged to be actuated by a plurality of the type-bars, and a supporting 105 member for said actuator pivoted on the segment.
- 50 16. In a typewriting machine, the combination with a main frame, a platen carriage, a carriage escapement, a series of pivoted type-bars, and a supporting segment for the type-bars, means for shifting said segment to place the type bars in different printing relations to the platen, and means for actuating the escapement comprising a 110 curved actuator movably mounted on the segment in position to be struck and moved by a plurality of the type-bars, substantially as set forth.
- 55 17. In a typewriting machine, the combination with a main frame, a platen carriage, a carriage escapement, a series of pivoted type-bars, and a supporting segment for the type-bars, means for shifting said segment to place the type-bars in different 115 printing relations to the platen, and means for actuating the escapement comprising a 120 curved actuator movably mounted on the segment in position to be struck and moved by a plurality of the type-bars, substantially as set forth.
- 60 18. In a typewriting machine, the combination with a main frame, a platen carriage, a carriage escapement, a series of pivoted type-bars, and a supporting segment for the type-bars, means for shifting said segment to place the type-bars in different 125 printing relations to the platen, and means for actuating the escapement comprising a 130 curved actuator movably mounted on the segment in position to be struck and moved by a plurality of the type-bars, substantially as set forth.

printing relations to the platen, and means for actuating the escapement comprising a bar adapted to be moved by a plurality of the type-bars and having an escapement 5 actuating part extending rearwardly therefrom, and a pivotal support for said bar, substantially as set forth.

18. In a typewriting machine, the combination with a main frame, a platen carriage, a carriage escapement, a series of pivoted type-bars, and a supporting segment for 10 the type-bars, of means for shifting said segment to place the type-bars in different printing relations to the platen, and means 15 for actuating the escapement comprising a curved actuator arranged to be actuated by a plurality of the type bars and to shift with said segment, and a pair of swinging supports for said actuator arranged one in rear 20 of the other and both in rear of said actuator, substantially as set forth.

19. In a typewriting machine, the combination with a main frame, a platen carriage, a carriage escapement, a series of pivoted type-bars, and a supporting segment for 25 the type-bars, of means for shifting said segment to place the type-bars in different printing relations to the platen, means for actuating the escapement comprising a 30 curved actuator arranged to be struck and moved by a plurality of the type-bars, and a pair of swinging supports for said actuator mounted one in rear of the other on said segment, substantially as set forth.

35 20. In a typewriting machine, the combination with a main frame, a platen carriage, a carriage escapement, a series of pivoted type-bars, and a supporting segment for the type-bars, of means for actuating 40 the escapement comprising an actuator arranged to be actuated by one or more of the type-bars and having a rearwardly extending bar, a pair of swinging supporting arms mounted on said segment and pivoted 45 to said rearwardly extending bar, and means adapted to be actuated by said bar for transmitting motion from said bar to said carriage escapement, substantially as set forth.

21. In a typewriting machine, the combination with a main frame, a platen carriage, a carriage escapement, a series of pivoted type-bars, and a shiftable supporting segment for the type-bars, of means for shifting said segment to place the type-bars 50 in different printing relations to the platen, and means for actuating said escapement comprising an actuator arranged to be moved by one or more of the type-bars having a rearwardly extending bar, a pair of 55 swinging supporting arms mounted on said shiftable segment and pivoted to said rearwardly extending bar, and means adapted to be actuated by said bar in the different 60 positions of the segment, substantially as 65 set forth.

22. In a typewriting machine the combination with a platen carriage, a series of pivoted type-bars, and a supporting segment for the type-bars, of a device to be actuated at each type stroke, an actuator supported by the segment and adapted to be actuated by one or more of the type-bars, and a universal bar supported independently of 70 said segment and moved by said actuator for operating said device, substantially as 75 set forth.

23. In a typewriting machine, the combination with a platen carriage, a series of pivoted type-bars, a shiftable supporting segment for the type-bars, and a carriage 80 escapement to be actuated at each type stroke, of an actuator supported by said segment and adapted to be actuated by one or more of the type-bars, and means moved by 85 said actuator in the different positions of said segment for transmitting motion from said actuator to said carriage escapement.

24. In a typewriting machine, the combination with a platen carriage, a series of pivoted type-bars, a shiftable supporting 90 segment for the type-bars, and a carriage escapement, of means for shifting said segment to place the type-bars in different printing relations to the platen, an actuator supported by said segment and adapted to 95 be actuated by one or more of the type-bars, and means supported independently of the segment and disconnected from said actuator but actuated thereby in the different positions of the segment for operating the 100 carriage escapement, substantially as set forth.

25. In a typewriting machine, the combination with a main frame, a platen carriage, a carriage escapement removably mounted 105 on and supported by said main frame, a series of pivoted type-bars, and a shiftable supporting segment for the type-bars, of means for shifting said segment to place the type-bars in different printing relations 110 to the platen, an actuator supported by the segment and adapted to be actuated by one or more of the type-bars, and means removably mounted on and supported by said main frame and disconnected from said actuator but actuated thereby correspondingly 115 in the different positions of said segment for operating said carriage escapement, substantially as set forth.

26. In a typewriting machine, the combination with a platen carriage, a series of pivoted type-bars, and a shiftable supporting segment for the type-bars, of a device 120 to be actuated at each type stroke, means for shifting said segment to place the type-bars in different printing relations to the platen, and means for actuating said device comprising an actuator supported by the segment and actuated by a plurality of the 125 type-bars, substantially as set forth.

27. In a typewriting machine, the combination with a platen carriage, a carriage escapement, a series of pivoted type-bars and a supporting segment for the type-bars, of means for actuating said carriage escapement comprising a universal bar, and an actuator for said universal bar supported by said segment and arranged to be actuated by a plurality of the type-bars, substantially as set forth. 70
28. In a typewriting machine, the combination with a platen carriage, a carriage escapement, a series of type-bars, and a shiftable supporting segment for the type-bars, of means for shifting said segment to place the type-bars in different printing relations to the platen, and means for actuating the carriage escapement comprising a universal bar, and a curved actuator for said universal bar mounted on the segment in position to be struck and moved by a plurality of the type-bars, substantially as set forth. 75
29. In a typewriting machine, the combination with a carriage escapement, a series of pivoted type bars, and a supporting segment for the type-bars, of means for actuating the carriage escapement comprising a universal bar, and a plurality of curved actuators for said universal bar mounted on said segment each in position to be struck and moved by a plurality of the type-bars, substantially as set forth. 80
30. In a typewriting machine, the combination with a platen carriage, a carriage escapement, a series of pivoted type-bars, and a shiftable supporting segment for the type-bars, of means for actuating the carriage escapement comprising a universal bar, and a plurality of curved actuators for said universal bar mounted on said segment each in position to be struck and moved by a plurality of the type-bars, substantially as set forth. 85
31. In a typewriting machine, the combination with a platen carriage, a series of pivoted type-bars, and a supporting segment for the type-bars, of a device to be actuated at each type stroke, and means for actuating said device comprising a curved actuator arranged to be actuated by a plurality of the type-bars, and a pair of swinging supports for said actuator pivotally mounted one in rear of the other on said segment, substantially as set forth. 90
32. In a typewriting machine, the combination with a platen carriage, a series of pivoted type-bars, and a supporting segment for the type-bars, of a device to be actuated at each type stroke, and means for actuating said device comprising a curved actuator arranged to be struck and moved by a plurality of type-bars, and a pair of swinging supports for said actuator pivotally mounted in rear of said segment and one in rear of the other, substantially as set forth. 95
33. In a typewriting machine, the combination with a platen carriage, a series of pivoted type-bars, and a shiftable supporting segment for the type-bars, of a device to be actuated at each type stroke, and means for actuating said device comprising a curved actuator arranged to be struck and moved by a plurality of the type-bars, and a pair of swinging supports for said actuator pivotally mounted on said shiftable segment one in rear of the other, substantially as set forth. 100
34. In a typewriting machine, the combination with a platen carriage, a series of pivoted type-bars, and a shiftable supporting segment for the type-bars, of a device to be actuated at each type stroke, means for shifting said segment to place the type-bars in different printing relations to the platen, and means for actuating said device comprising a universal bar, and a plurality of curved actuators supported by the segment each in position to be actuated by a plurality of said type-bars, substantially as set forth. 105
35. In a typewriting machine, the combination with a platen carriage, a series of pivoted type bars, and a shiftable supporting segment for the type-bars, of means for shifting said segment to place the type-bars in different printing relations to the platen, a universal bar, and means for actuating said universal bar in the different positions of the segment comprising a curved actuator arranged to be actuated by a plurality of the type bars, and supporting means for said actuator comprising a rock shaft mounted on the segment and having arms pivotally connected to said actuator, substantially as set forth. 110
36. In a typewriting machine, the combination with a platen carriage, a series of pivoted type-bars, and a shiftable supporting segment for the type bars, of an actuator arranged to be struck and moved by one or more of the type-bars and having a rearwardly extending bar, a pair of swinging supporting arms for said actuator pivoted to said rearwardly extending bar, a universal bar adapted to be engaged and moved by said rearwardly extending bar in the different positions of said segment, substantially as set forth. 115
37. In a typewriting machine, the combination with a platen carriage, a series of pivoted type-bars, and a supporting segment for the type bars, of a device to be actuated at each type stroke, and an actuator supported by the segment and arranged to be struck and moved by one or more of the type bars, and a universal bar supported independently of said segment and disconnected from said actuator but ac- 120

tuated thereby for operating said device, substantially as set forth.

38. In a typewriting machine, the combination with a platen carriage, a series of pivoted type-bars, and a shiftable supporting segment for the type-bars, of a device to be actuated at each type stroke, an actuator supported by said segment and arranged to be actuated by one or more of the type-bars, and a universal bar supported independently of the segment and actuated by said actuator in the different positions of the segment for operating said device, substantially as set forth.
39. In a typewriting machine, the combination with a platen carriage, a series of pivoted type-bars, a supporting segment for the type-bars, a carriage escapement, and a ribbon vibrator, of an actuator supported by the segment and adapted to be actuated by one or more of the type-bars, and a device which is actuated by said actuator for operating said escapement and said ribbon vibrator and which is shiftable for changing the action of the ribbon vibrator without affecting the action of said escapement, substantially as set forth.
40. In a typewriting machine, the combination with a main frame having a removable top plate, a platen carriage, a carriage escapement supported by said top plate, a series of pivoted type-bars, and a supporting segment for the type-bars, of an actuator supported by the segment and adapted to be actuated by one or more of the type-bars, and means supported by said top plate and disconnected from said actuator but actuated thereby for operating

said carriage escapement, substantially as set forth.

41. In a typewriting machine, the combination with a main frame, a platen carriage, a carriage escapement supported by said main frame, a ribbon vibrator supported by said main frame, a series of pivoted type-bars, and a supporting segment for the type-bars, of an actuator supported by the segment and adapted to be actuated by one or more of the type-bars, and means supported on the main frame for operating said carriage escapement and said ribbon vibrator, said carriage escapement, ribbon vibrator and said operating means being removable from the machine without disturbing said segment and the parts supported thereby, substantially as set forth.

42. In a typewriting machine, the combination with a main frame, a platen carriage, a carriage escapement, a series of pivoted type-bars, and a supporting segment for the type which is shiftable to place the type-bars in different printing relations to the platen, of means for actuating the escapement comprising a bar arranged to be actuated by a plurality of the type-bars and having a rearwardly extending actuating part for the escapement, said bar being mounted to shift with the segment, substantially as set forth.

Witness my hand, this 11th day of February, 1911.

EMMIT G. LATTA.
